C. F. LEFEVER

AIR GUN

Filed Sept. 22, 1924

Charles F. Lefever

Inventor

By Whittmore Hulbert Whittmore
+ Belknap Attorneys

UNITED STATES PATENT OFFICE.

CHARLES F. LEEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

AIR GUN.

Application filed September 22, 1924. Serial No. 739,170.

To all whom it may concern:

Be it known that I, CHARLES F. LEEFEVER, a citizen of the United States of America, residing at Plymouth, in the county of Wayne 5 and State of Michigan, have invented certain new and useful Improvements in Air Guns, of which the following is a specification, reference being had therein to the accompanying drawings.

10 This invention relates to guns and particularly relates to air guns.

It is an object of the invention to provide an improved mounting for the closure controlling the opening in the barrel of an air 15 gun through which shot may be introduced into a magazine within said barrel.

A further object is to derive a novel reinforcing function from a guide member for shot mounted upon a tube into which it 20 guides the shot and through which the shot are discharged.

These and various other objects the invention attains by the construction hereinafter described and illustrated in the accompanying 25 drawing, wherein:

Figure 1 is a plan view, partially in section, of an air gun barrel embodying the invention.

Figure 2 is a view of the same in axial 30 sectional elevation.

Figure 3 is a cross sectional view taken upon the line 3—3 of Figure 2.

In these views, the reference character A designates the false barrel of an air gun, 35 and B the usual true barrel or shot tube extending centrally through said barrel. Between said tube and barrel, there is formed a magazine chamber C for shot, an opening D being formed in the barrel adjacent its outer end for insertion of the shot. E is a closure for said opening formed by a free end of spring sheet-metal arm E' disposed within the barrel A, the other end of said arm being welded or otherwise suit- 40 ably secured to a cap F which substantially closes the outer end of the barrel A. Said cap has a marginal cylindrical flange which fits into the barrel A, and preferably the arm E' is carried by said flange. The cap 45 F has a central opening and is formed with a cylindrical flange G, marginally of said opening, and projecting into the barrel A, the outer end of the tube B being inserted in said flange G and secured thereto by 50 brazing or the like.

H is a collar mounted fast upon the inner end of the tube B and externally threaded for engagement centrally with a disk H' fixed within the barrel A, the inner end of said tube being thus supported in its proper 60 central relation to said barrel. Adjacent to said collar the tube B is formed with a shot inlet I and a sheet metal guide member J is mounted fast upon said tube for directing the shot into said opening from the 65 magazine C. Said guide is of an approximate U-shape, the tube B being extended through its lower portion and being brazed or otherwise suitably rigidly secured to said portion. Portions of said guide projecting 70 above the tube coact with the latter to form a run-way through which shot may travel toward the opening I.

The presence of the opening I in the tube B tends considerably to weaken said tube, 75 and if the end of the tube adjacent said opening were directly inserted in the collar H, there would exist a possibility of the tube being bent at said opening if roughly or improperly handled. As a safe-guard 80 against such damage, the guide J is integrally formed, at its inner end with a split bushing K which fits into and is secured within the collar H, the inner end of the tube being inserted in said bushing and secured therein. Thus the shot guide reinforces the tube at its weakest point in addition to directing the shot to the inlet located at said point.

It is an advantage of the structural features above described that they facilitate the uniting of the described parts by brazing instead of soldering and this in turn has the advantage that the structure may be subjected to a higher temperature in bluing 95 than would be possible with a soldered connection.

What I claim as my invention is:

1. In a device of the character described, a gun barrel having an opening adjacent one end thereof for the insertion of shot, a cap forming a closure for said end of the barrel, a closure for said opening, and a spring arm carrying said closure at one end and mounted at its other end upon said cap. 100
2. In a device of the character described, a gun barrel formed with an opening adjacent one end thereof, a cap forming a closure for said end of the barrel, and a closure for said opening mounted upon said cap and yield- 110

- able into the barrel to permit the insertion of shot through said opening.
3. In a device of the character described, a gun barrel formed with an opening adjacent one end thereof, a cap substantially closing said end and having a flange fitted within the barrel, a closure for said opening, and a spring arm mounted upon said flange and carrying said closure.
- 10 4. In a device of the character described, a gun barrel, a shot tube extending through said barrel and having an opening for the admission of shot thereto, and a shot guide mounted upon said shot tube at one side of said opening formed with a bushing embracing said tube at the other side of said opening.
- 15 5. In a device of the character described, a gun barrel, a shot tube extending through said barrel and having an opening for the

admission of shot thereto, a member fixed within said barrel forming a support for said tube at one side of said opening, and a shot guide mounted upon said tube at the other side of said opening and having a 25 portion embracing the tube within said fixed member.

6. In a device of the character described, a gun barrel, a shot tube extending through said barrel and having an opening for the 30 admission of shot to said tube, a shot guide mounted upon said tube at one side of said opening, a support for the tube fixed within the barrel at the other side of said opening, and a collar rigidly carried by the tube for engagement with said support, said shot guide having an integral portion engaged within said collar.

In testimony whereof I affix my signature.
CHARLES F. LEFEVER.
